UNITED STATES PATENT OFFICE.

JOHN HOSZOWSKI, OF OAKLAND, CALIFORNIA.

FOLDING TABLE.

Application filed November 25, 1922. Serial No. 603,207.

My invention is an improved folding table. The object of my invention is to provide a table which is simple in construction and inexpensive to manufacture.

5 Referring now to the drawing:

Figure 1 is a side view of my table in a folded position.

Figure 2 is a bottom plan view of the table top in unfolded position.

10 Figure 3 is a perspective view of the table.

Figure 4 is a fragmentary side view partly in section of one of the leg and top connections.

15 Figure 5 is a sectional view taken on the line 5—5 of Figure 3.

Referring more particularly to the drawing:

The numeral 1 indicates a top which is formed of boards 2, 3, 4 and 5. The boards 20 2 and 3 are hinged together by hinges 6, the boards 3 and 4 by hinges 7 and the boards 4 and 5 by hinges 8. A stiffening bar 9 is pivoted on a plate 10 which is secured to the board 2. In the folded position the bar 9 is 25 held under a spring clip 11 on the board 2. A stiffening bar 12 is pivoted to a plate 13 which is secured to the board 5 at the opposite side of the table from the bar 9. In the folded position the bar 12 is held by a clip 30 14 on the board 5. In the open position the bar 9 fits under a plurality of plates 15 which plates are secured to each of the boards 2, 3, 4 and 5, and a spring clip 16 on the board 5 engages the side of the said bar to hold it 35 under the said plates. The bar 12 fits under a plurality of plates 17 secured to the boards 2, 3, 4 and 5, and is held under said plates by a spring clip 18 on the board 2 which en-

gages the side of said bar. It will be seen that when the bars 9 and 12 engage the plates 40 15 and 17 respectively, the boards 2, 3, 4 and 5 will be held in absolute alignment in an extended or unfolded position.

Lugs 19 and 20 are secured to the board 5 and a lug 21 is secured to the board 2. The 45 legs 22, 23 and 24 are tubular in form and are adapted to engage the lugs 19, 20 and 21 to support the top 1. The legs 22, 23 and 24 are hinged together by a spider 25, the legs of which extend through the legs and 50 are held in place by cotter pins 26. Spacing rods 27, 28 and 29 are secured to the legs 22, 23 and 24 respectively and to a central ring 30.

Having described my invention, I claim: 55

In combination a table plate comprising a plurality of leaves hinged alternately on opposite sides so as to be adapted for folding to the width of a single leaf, legs supporting the outer leaves and engaging the same at an angle so that the legs intersect substantially at the center of the table midway of the height thereof, means for tying the legs at the intersection and bars pivoted to the outer leaves at diametrically opposed corners, each being adapted to be swung outward from a parallel position and around the corner into a transverse position for supporting all the leaves, the leaves having aligned clips adapted to receive the bars and springs being positioned in the path of the bars so as to be passed and depressed by the latter and to rebound after the bars have passed for locking the same in place. 60 65 70

In testimony whereof I affix my signature.

JOHN HOSZOWSKI.
